CLAIM

The ornamental design for a broom, as shown and described.

DESCRIPTION

FIG. 1 is a front perspective view of a broom according to the invention.

FIG. 2 is a front view of the broom of FIG. 1.

FIG. 3 is a rear view of the broom of FIG. 1.

FIG. 4 is a left side view of the broom of FIG. 1.

FIG. 5 is a right side view of the broom of FIG. 1.

FIG. 6 is a top plan view of the broom of FIG. 1; and,

FIG. 7 is a bottom plan view of the broom of FIG. 1.

The broken lines in the figures represent portions of the broom that form no part of the claimed design.

1 Claim, 7 Drawing Sheets(56)
